UNITED STATES PATENT OFFICE.

OLIVER LABAN BULLOCK, OF CHERRYVILLE, MISSOURI.

CHURN.

SPECIFICATION forming part of Letters Patent No. 665,669, dated January 8, 1901.

Application filed July 14, 1900. Serial No. 23,630. (No model.)

To all whom it may concern:

Be it known that I, OLIVER LABAN BULLOCK, a citizen of the United States, residing at Cherryville, in the county of Crawford and State of Missouri, have invented a new and useful Churn, of which the following is a specification.

My present invention relates to improvements in churns, and has for its object the production of a device of this character embodying dasher-operating mechanism designed to accomplish the churning of butter in a minimum space of time and a churn-body removably retained in the frame of the machine by a simple and conveniently-operated mechanism and comprehending within the churn-body a butter-pan designed to facilitate the removal and draining of the butter after the churning operation has been completed.

To the accomplishment of these ends the invention consists in the construction and arrangement of parts hereinafter described, illustrated in the accompanying drawings, and defined in the appended claims.

In said drawings, Figure 1 is a perspective view of my churn complete. Fig. 2 is a sectional plan view designed with special reference to the illustration of the manner in which the churn-body is removed from the frame. Fig. 3 is a central vertical section through the device complete. Fig. 4 is a detail view of the cover detached. Fig. 5 is a similar view of one of the dashers and its staff, and Fig. 6 is a detail plan view of the butter-pan.

Referring to the numerals of reference employed to designate corresponding parts in the several views, 1 indicates the platform, designed for the reception of the churn-body and preferably mounted upon side rails 2, from which extend a pair of parallel vertical side frames 3, preferably constructed of light metal and bifurcated at their opposite ends, as shown. Each of the side frames 3 is surmounted by a head-beam 4, and they are retained in spaced relation by bolts or stay-rods 5, extending between the head-beams 4 and preferably serving to connect the ends of the side frames 3 with said beams. At a suitable distance below the head-beams is located a horizontal head-plate 6, having flanges 7 at

its opposite ends bolted to the frames 3 and also provided at or about the longitudinal center of the plate with an elongated slot 8, accessible through a wide throat 9, formed by cutting away the front edge of the plate 6 at the center.

The frame of the machine thus constructed is designed for the support of the operative parts of the churn, the body being designed for location upon the platform 1 and the dasher-operating mechanism being mounted above the head-plate 6 for operative connection with the dasher-staffs, which project upwardly through the slot 8 in the head-plate, as will be hereinafter more fully described. For the retention of the churn-body 10, which is preferably of cylindrical form, the platform is provided adjacent to its rear end with a raised seat-block 11, having a semicircular seat 12, formed by imparting a concave curvature to its front face. The churn-body 10 is designed to rest upon the platform and against the seat 12, where it is retained by a spring-latch 13, secured at one end under the platform 1, as seen in Fig. 3, and having an angular beak 14 extending upwardly through a recess 15 in the platform 1 and impinging against the front of the churn for the purpose of holding the latter rigidly against the seat 12. For the purpose of preventing axial movement of the churn, except when the latch 13 is depressed, the churn is provided at its lower edge at a point opposite the beak 14 of the latch with a horizontal projection 16 extended into a recess or socket 17 in the curved front face 12 of the seat-block 11.

The churn-body is provided with a circular cover 18, provided with a pair of diametrically-aligned slots 19 for the accommodation of the dasher-staffs 20 and 21, these slots being so related that they will be presented directly under the ends of the slot 8 of the head-plate 6 when the churn is in place. For the purpose of additionally securing the churn-body and to facilitate its removal from the machine and the removal of the cover from the body said cover is provided with a handle 22, projecting beyond its periphery and formed at one end of a handle-bar 23, extending diametrically across the top of the cover, at right angles to the slots 19 and intermediate thereof, said handle-bar 23 being cut away at its

rear end and formed with a shoulder 24, designed, when the churn-body is seated, to abut against the edge of the head-plate 6 defined by the rear edge of the slot 8.

5 Surmounting the head-beams 4 are a pair of journal-boxes 25, constituting bearings for a crank-shaft 26, having a pair of oppositely-disposed cranks 27 and 28 and provided upon its opposite ends, beyond the head-beams 4, 10 with a fly or balance wheel 29 and a spur-pinion 30. The pinion 30 is intermeshed with a comparatively large gear-wheel 31, mounted upon a short stud-shaft 32, projecting from one of the side frames 3, the gear-wheel 32 15 being the driving-wheel of the operating mechanism and having extending therefrom an operating-crank 33, through the manipulation of which the crank-shaft 26 may be rotated at a high rate of speed. The cranks 27 and 28 20 are operatively connected, through pitmen 34 and 35, with a pair of reciprocatory cross-heads 36 and 37, each mounted to reciprocate between upstanding guides or ways 38, which may be and preferably are short metal rods 25 supported at their lower ends upon the head-plates 6. Inasmuch as the cross-heads are mounted to reciprocate directly above the churn-body, each of the guides 38 is provided at its lower end, immediately above the plate 30 6, with a drip-cup 39, designed to prevent the lubricant employed in connection with the cross-heads from finding its way through the openings in the cover of the churn. The cross-heads 36 and 37 are designed to be connected, 35 respectively, to the dasher-staffs 20 and 21, and as this connection must obviously be capable of release to facilitate the removal of the churn-body when necessary each cross-head is pierced by a vertical staff-socket 40 40 and is provided with an abutment-screw 41, extending into the socket from the exterior of the cross-head for the purpose of adjustably securing the staff for reciprocation with the cross-heads as the latter are operated in the 45 manner specified.

Various forms of dashers may be employed in connection with a churn of the peculiar construction described; but I prefer to construct each of these dashers in the form of a 50 numerously-perforated plate 42, secured at the lower end of each staff and designed as the staffs are reciprocated in opposite directions to violently agitate the contents of the churn-body for the purpose of producing butter in a minimum space of time. In order to facilitate the draining and removal of the butter when the churning is completed, I provide a shallow butter-pan 43 at the bottom of the churn-body 10, said pan being 55 provided with a perforated bottom 44 and having an upstanding axial handle-rod 45, bent at its upper end to form a ring or finger-hold 46, which may be grasped to lift the pan from the churn-body after the cover has been 60 removed.

65 The operation of my device is as follows: The churn-body having been placed in posi-

tion upon the platform and the dasher-staffs having been connected to the cross-heads, the crank 33 is grasped by the operator and the 70 rotation of the gear-wheel 31 at a moderate speed will cause the rotation of the crank-shaft 26 and the reciprocation of the cross-heads 36 and 37 at a comparatively high rate of speed by reason of the differential diameters of the wheel 31 and the pinion 30. The connection between the dasher-staffs and cross-heads will cause the dashers to be rapidly reciprocated in opposite directions within the churn-body to effect the churning of butter in a minimum space of time and with a minimum expenditure of power. When the churning operation has been completed, the dasher-staffs are released from the cross-heads by unscrewing the set-screws 41. The 80 staffs are then urged toward the handle-bar 23 to facilitate their removal through the throat 9 into the slot 8 of the head-plate. The latch 13 is now depressed to remove the beak from its obstructing position and the churn-body is drawn forward to release the projection 16 of the churn-body from the socket 17, formed in the seat-block. The churn-body 85 now being free to rotate a slight axial movement is imparted thereto for the purpose of presenting one of the dasher-staffs to the throat 9. The churn-body is now drawn forward to remove the dasher-staffs from the slot 8, through the throat 9, and after the churn-cover has been entirely removed from 90 under the head-plate 6 said cover and the dashers may be removed to facilitate the removal of the butter by the raising of the butter-pan.

95 From the foregoing it will be observed that I have produced a simple, durable, and highly-effective churn, comprehending means for operating the dashers at a high rate of speed, means for rigidly retaining the churn-body in place during the churning operation, and means for effecting the simultaneous straining and removal of the butter after the churning is completed; but while the present embodiment of my invention appears at this time to be preferable I desire to be understood 115 as reserving the right to effect such changes, modifications, and variations of both form and arrangement as may be suggested by experience and experiment, provided they are embraced within the spirit of the invention. 120

125 What I claim is—

1. In a churn, the combination with a frame comprising a head-plate having a longitudinal slot and a transverse throat opening into the slot at its middle, of a churn-body, dashers therein, and dasher-staffs, said staffs being designed for presentation to the slot in the head-plate through the throat and to be located in the opposite ends of the slot, dasher-operating mechanism mounted above the dasher-plate, and means for detachably connecting said mechanism to the dasher-staffs. 130

2. In a churn, the combination with a frame comprising a head-plate having a longitudi-

nal slot and a transverse throat opening there-
in at its middle, of a churn-body, dasher-
staffs extending above the churn-body and
designed for lateral presentation to the slot
5 in the head-plate through the throat, dasher
mechanism located above the head-plate and
detachably connected to the staffs, and means
for retaining the churn-body against axial
movement to prevent the withdrawal of the
10 dasher-staffs from the head-plate.

3. In a churn, the combination with a frame
comprising a head-plate having a longitudi-
nal slot and a transverse throat opening into
the slot at its middle, of a churn-body pro-
15 vided with a pair of elongated openings dis-
posed below the opposite ends of the slot in
the head-plate, dashers within the churn-
body, and dasher-staffs extending therefrom,
said staffs being arranged to be drawn to the
20 inner ends of the openings in the churn-cover
for presentation to the throat of the head-
plate.

4. In a churn, the combination with a frame
comprising a head-plate having a longitudi-
nal slot and a transverse throat opening into 25
the slot at its middle, of a churn-body pro-
vided with a cover having a pair of elongated
openings, dasher - staffs extending through
said openings and located within the opposite
ends of the slot in the head-plate, and cross-
30 heads movable above the opposite ends of the
slot and designed to be detachably engaged
to the dasher-staffs when the latter have been
passed through the throat and have been
moved to positions at the opposite ends of the 35
slot.

In testimony that I claim the foregoing as
my own I have hereto affixed my signature in
the presence of two witnesses.

OLIVER LABAN BULLOCK.
